United States Patent

Des. 240,481
Patented July 13, 1976

240,481

SOFA

Lee Harold Fister, Jr., 7715 Park Creek Drive,
Dayton, Ohio 45459

Filed Feb. 10, 1975, Ser. No. 548,233

Term of patent 14 years

Int. Cl. D6—01

U.S. Cl. D6—61

FIG. 1 is a frontal perspective view of a sofa constructed in accordance with the invention;
FIG. 2 is a side and rear perspective view thereof;
FIG. 3 is a top plan view thereof;
FIG. 4 is a side view thereof;
FIG. 5 is a bottom plan view thereof.

I claim:
The ornamental design for a sofa, as shown.
